UNITED STATES PATENT OFFICE.

OTTO H. LINDENBERG, OF COLUMBUS, OHIO.

DESIGN FOR A MEDAL.

Application filed February 19, 1923. Serial No. 5,203. Term of patent 14 years.

To all whom it may concern:

Be it known that I, OTTO H. LINDENBERG, a citizen of the United States, residing at Columbus, in the county of Franklin and State of Ohio, have invented a new, original, and ornamental Design for Medals, of which the following is a specification, reference being had to the accompanying drawing, forming part thereof.

I claim:

The ornamental design for a medal, as shown.

OTTO H. LINDENBERG.
